UNITED STATES PATENT OFFICE

136,407

DESIGN FOR A WIRE FENCE TOOL

Abner D. Duncan, Ponca City, Okla.

Application April 22, 1943, Serial No. 110,017

Term of patent 14 years

To all whom it may concern:

Be it known that I, Abner D. Duncan, a citizen of the United States, residing at Ponca City, in the State of Oklahoma, have invented a new, original, and ornamental Design for a Wire Fence Tool, of which the following is a specification, reference being had to the accompanying drawing, forming part thereof.

In the drawing:

Fig. 1 is a side elevation of a wire fence tool showing my new design.

Fig. 2 is a top plan view of the same.

Fig. 3 is a bottom plan view of the wire fence tool.

Fig. 4 is a front end elevation thereof.

I claim:

The ornamental design for a wire fence tool, as shown.

ABNER D. DUNCAN.
